(57) **CLAIM**

The ornamental design for a product display, as shown and described.

DESCRIPTION

FIG. 1 is a perspective view of a product display, according to an embodiment of the invention.

FIG. 2 is a front view of a product display, according to an embodiment of the invention.

FIG. 3 is a back view of a product display, according to an embodiment of the invention.

FIG. 4 is a right end view of a product display, according to an embodiment of the invention. A left end view of a product display, according to an embodiment of the invention, is an identical, mirror image of FIG. 4, and is omitted.

FIG. 5 is a top view of a product display, according to an embodiment of the invention; and,

FIG. 6 is a bottom view of a product display, according to an embodiment of the invention.

The broken lines are for the illustrative purposes only and form no part of the claimed design.
